I. E. McCABE ET AL

MERCURY SWITCH

Filed Oct. 22, 1924

UNITED STATES PATENT OFFICE.

IRA E. McCABE AND RAYMOND W. ARMSTRONG, OF CHICAGO, ILLINOIS; SAID ARMSTRONG ASSIGNOR TO THE ARCLESS CONTACT COMPANY, A CORPORATION OF ILLINOIS.

MERCURY SWITCH.

Application filed October 22, 1924. Serial No. 745,134.

Mercury switches in which contact is intended to be made and broken between mercury and a solid terminal have been developed to a degree that insures them extremely long life without deterioration. For some purposes it is desirable that the circuits be made and broken between two bodies of mercury, the usual construction involving the use of a small well in the bottom of the switch tube or casing, the well being intended always to remain full of mercury. In this latter type of switch the current has usually been carried to and from the switch through a small leading-in wire projecting into the well through the bottom thereof; this construction being admirable under ordinary conditions. However, it not infrequently happens that the mercury flows out of the well when the switch is tilted beyond a predetermined angle and, if current is then flowing, the break occurs and the arc is formed between the small leading-in wire and the mercury. When arcing occurs between a small leading-in wire and the mercury, the leading-in wire is burned away wholly or in part, breaking the seal between the wire and the wall of the tube or receptacle into which the wire extends, allowing air to enter. Therefore, even though the switch may continue to operate thereafter, the mercury will be sluggish through oxidation.

The object of the present invention is to produce a switch of the type in which contact is made and broken between two bodies of mercury, which shall be free from the objections heretofore noted and which shall continue to function in an unimpaired condition even though the interruption of the circuit at times occurs between mercury and a solid terminal.

We accomplish this object by making each terminal of a switch a double terminal which consists of a primary terminal of mercury and a secondary terminal of solid metal normally immersed in the primary terminal and so located and proportioned as to serve not only as a current carrier but also as an element designed and adapted to withstand arcing and also keep the arc away from the walls of the receptacle in the event that the primary terminal fails and thus causes the secondary terminal to become the primary.

Our invention has another aspect. The

bodies or casings of the best types of mercury switches are made of glass and are hermetically sealed. The leading-in wires must therefore be sealed through the glass. It is comparatively easy to make a perfect seal around a small wire but, as the size of the wire increases, difficulty is experienced in making such a seal. Therefore when large currents are to be carried, necessitating the use of large leading-in wires, it has not been easy properly to seal the wires in the glass. Viewed in one of its aspects our invention may be said to have for its object to produce a simple and novel mercury switch having large leading-in wire capacity, without being open to the objection that it is difficult to form a seal between the wires and the glass.

In carrying out this latter feature of our invention, we substitute for each single leading-in wire a plurality of wires passing through the glass at points remote from each other so that each may be sealed without affecting the seal of the other wire or wires; the inner ends of what may be termed each multiple leading-in wire being so located relatively to each other as to constitute, in effect, a single terminal.

The various features of novelty whereby our invention is characterized will herein-after be pointed out with particularity in the claims; but, for a full understanding of our invention and of its objects and advantages, reference may be had to the following detailed description taken in connection with the accompanying drawing, wherein:

Figure 1 is a side view of a mercury switch embodying the present invention in a simple form; Fig. 2 is a longitudinal vertical section through the switch shown in Fig. 1; Fig. 3 is a view similar to Fig. 2, showing a modification; and Fig. 4 is a view similar to Figs. 2 and 3, illustrating not only a simple form of the invention but also the form containing multiple leading-in wires.

Referring to Figs. 1 and 2, 1 represents a sealed glass tube having in the bottom, at points remote from each other, two small wells, 2 and 3. Leading-in wires 4 and 5 pass through the upper side of the tube, one directly above each well. On the inner end of each leading-in wire is an enlarged head or terminal, these being indicated at 6 and 7; these heads or terminals being made of

pure iron or other metal suitable for this purpose. The heads are spaced apart from the wall through which they pass by means of sleeves of glass 8 surrounding the inner ends of the leading-in wires. These heads or terminals extend into the mouths of the wells a slight distance, in fact, terminate immediately below the brim of the well, as clearly shown upon the drawing. In the tube is a body of mercury that only partially fills the same. The remainder of the space is filled with a suitable gas, such as hydrogen. In the position of the switch illustrated, the mercury is divided into two bodies 9 and 10, the former filling the well 2 and extending part way to the well 3, while the other simply fills the well 3. The head or terminal 6 is immersed in the larger of the two bodies, while the head or terminal 7 projects into the smaller body of mercury in the well 3. This is the condition that exists at the time the circuit is broken so that, as will be seen, the arcing that takes place is between the two bodies of mercury. If however, the right hand end of the tube had been swung downwardly far enough to permit the mercury to flow out of the well 3 before any break had occurred in the mercury to separate it into two bodies, the circuit would eventually have been broken between the mercury and the head or terminal 7. However, the terminal 7, having a construction similar to that of a terminal in a mercury switch wherein the making and breaking of the circuit is always between mercury and the solid terminal, and being spaced apart from the glass wall of the tube, no damage can result to the terminals or to the seal or to the glass from the abnormal use of the switch.

After repeated operation of the switch the solid member of the terminal at which the circuit is broken becomes coated with a film of mercury, so that the mercury in the corresponding well climbs up somewhat on this member when the switch is tilted to open position, causing the arc to be made at a point more remote from the glass than would be the case if the solid terminal member were not present, and protecting the glass from the arc.

In the switch shown in Fig. 3, one of the wells is omitted. Referring to this figure, 11 represents the tube and 12 a well opening out of the bottom thereof at or near the end. 13 and 14 are leading-in wires entering the tube through the upper side of the tube. 15 and 16 are enlarged heads or terminals on the inner ends of the leading-in wires projecting slightly into the well 17 and terminating immediately below the brim thereof. The mercury is indicated as divided into two bodies 17 and 18, the former being a small body filling the well; this being the open position. It is immaterial whether or not

the member 16 remains in contact with the body of mercury 18 when the switch is tilted to break the circuit, because the interruption of the circuit occurs when the mercury divides into two bodies and no current is passing through the member 16 thereafter. If the switch is tilted too far in opening it, spilling the mercury out of the well, the interruption of the circuit is efficiently effected at the head 15.

The switch shown in Fig. 4 is a combination of the switch shown in Figs. 1 and 2 and another simple modification. In other words, it is the switch of Figs. 1 and 2 having additional leading-in wires or terminals 80 entering the wells through the bottom. The tube is indicated at 21 and the wells at 22 and 23. Terminals 24 and 25 similar to the terminals 6 and 7 in Fig. 2 are secured to leading-in wires 27 and 28 extending through the top of the tube above the wells and project slightly into the wells, terminating immediately below the brim thereof. Other terminals, 29 and 30, are located in the wells and secured to leading-in wires 31 and 32 passing upwardly through the bottoms of the wells. The terminals are spaced apart from the glass bottoms of the wells by glass sleeves 33. The mercury is shown as divided into two bodies 9 and 10 as in Fig. 2, the switch being shown open. It will be seen that the terminals 24 and 29 are immersed in the larger body of mercury, while the terminals 25 and 30 may contact with the smaller body 90 of mercury in the well 23. The break in the circuit has therefore taken place between mercury and mercury. In the event of the tipping of the switch far enough in either direction to empty either well, while current is flowing, the break will occur between the corresponding pair of heads or terminals and mercury, no damage resulting.

The leading-in wires of each pair of terminals are adapted to be connected together outside of the switch so that no one terminal or leading-in wire is required to carry more than one-half of the current flowing through the switch. This permits the leading-in wires to be made much smaller than would be the case if each wire had to carry the entire current and therefore the leading-in wires need not be so large as to make difficult the sealing of the same in the glass. Furthermore, the seals are all remote from each other, so that the heating of the glass while making one of the seals does not affect the glass at any of the other seals. The arrangement shown is one of the simpler forms illustrating the use of what may be termed a multiple leading-in wire, but it will of course be understood that this idea may be extended and elaborated.

In all forms illustrated the terminals above the wells enter a slight distance into

the mouth of each well and terminate immediately below the brim thereof whereby should the tipping of the switch be far enough to empty the well upon tipping in 5 the opposite direction the mercury will first fill the well and then engage the terminal and in the event that an air pocket be formed in the bottom of the well the mercury supported thereabove will engage the terminal 10 and contact will be established to the other terminal.

While we have illustrated and described with particularity only a few simple forms of our invention, we do not desire to be 15 limited to the exact structural details thus illustrated and described but intend to cover all forms and arrangement coming within the definitions of our invention constituting the appended claims.

20 We claim:

1. A mercury switch including a horizontal tubular casing having two wells in the bottom side, a body of mercury only partially filling the casing, a leading-in wire 25 passing into each well through a wall of the same, a large head or terminal on the inner end of each of the aforesaid wires, a second leading-in wire passing through the upper side of the casing above each well,

and a large head or terminal on each of said 30 second wires projecting slightly into the mouths of the wells and terminating immediately below the brims thereof, whereby both heads or terminals at each well will be in contact with the mercury in the well when 35 the latter is full.

2. A mercury switch comprising a casing in the form of a sealed tube having a small well opening out of one side of the tube, a body of mercury only partially filling the 40 casing but in excess of the capacity of the well, a leading-in wire extending through the side of the tube opposite the well, a large head or terminal secured on the inner end of said leading-in wire and projecting 45 slightly into the well and terminating immediately below the brim thereof, and a second terminal located in position to engage with the mercury when it is united in one body and remain in engagement with the 50 main portion of the mercury when the casing is tilted so as to separate the main portion of mercury from that in the well.

In testimony whereof, we sign this specification.

RAYMOND W. ARMSTRONG.
IRA E. McCABE.
